PREPARATION OF VITAMIN COMPOSITIONS

Kenneth C. D. Hickman, Rochester, N. Y., assignor, by mesne assignments, to Distillation Products, Inc., Rochester, N. Y., a corporation of Delaware

No Drawing. Application March 15, 1938,
Serial No. 196,031

6 Claims. (Cl. 202—52)

This invention pertains to the preparation of therapeutic concentrates by high vacuum distillation of organic oils and is in part a continuation of my U. S. application 37,751, filed August 24, 5 1935.

It is known that vitamin concentrates can be economically produced by high vacuum distillation of organic oils such as fish oils containing such substances. In general the procedure involves heating the oil, preferably in a thin film 10 to distillation temperature under a high vacuum and condensing vaporized molecules upon a condensing surface separated from the vaporizing zone by substantially unobstructed space. The 15 distance between the vaporizing zone and the condensing surface should preferably be less than about the mean free path of the residual gases present in the distillation chamber. In practice short distances of less than 12 inches, such as $\frac{1}{2}$ to 4 inches are most generally satisfactory. Pressures of residual gas below 1 mm. and especially below .1 mm. such as .005—.001 mm. are usually employed.

In carrying out these distillations I have found 25 that free fatty acids are obtained in concentrated form in some of the lower fractions containing vitamins. The fatty acids are in the main the same as those which were present in free form prior to the distillation. These materials distill 30 at temperatures below about 170° and especially at about 110—160° C. Considerable amounts of the vitamins distill at these same temperatures. These mixed distillates have rather low value because of their high acid content and taste.

This invention has for its object to overcome 35 the above difficulties. Another object is to provide an improved process which will yield high vacuum distillates substantially free of fatty acids. A further object is to provide a process for preparing vitamin distillates in improved form, for instance such that have improved taste and/or ingestible qualities. Other objects will appear from the following description.

These and other objects are accomplished in 45 accordance with my invention which, in general, comprises substantial neutralization of the free acid content of the vitamin-containing oil prior to distillation to separate the vitamin content of the oil. This treatment results in the substantial removal of fatty acids and acts to improve the quality of the distillates.

In the following examples and description I have given several of the preferred embodiments 50 of my invention, but it is to be understood that

these are given for the purpose of illustration and not as limitations thereof.

The oil, such as for instance a fish oil from which the vitamins are to be distilled, is treated with an alkali in amounts sufficient to substantially neutralize free fatty acids contained therein. A slight excess of the base, of approximately 20% is advantageous. However, it is desirable that amounts sufficiently large to cause substantial saponification of the oil, be avoided. Substantially greater amounts cause decomposition or conversion of vitamin esters into lower boiling undesirable forms as well as loss of valuable oil. The amount of alkali required can be readily determined by preliminary titration of a small 15 sample of the oil. I prefer to use aqueous solutions of the alkaline compound, but this is unnecessary since solid alkali can be added, and the oil separated from the solid soaps formed. Alkalies usually employed for neutralization can 20 be used. Examples are sodium, potassium, lithium, calcium, etc. hydroxides; sodium carbonate, ammonium hydroxide, etc., "modified alkalies" such as the basic silicates, phosphates, sesqui carbonates, etc., are also useful.

After addition of the alkaline solution, the mixture is agitated until the oil has been thoroughly contacted with the alkali and the acids neutralized. It is desirable, but not essential, to warm the mixture slightly during this period. A 30 temperature of about 40° C. is satisfactory. This results in an improved soap precipitation and a clearer oil. When the acids have been neutralized the agitation is discontinued and the oil allowed to settle. The oil is then decanted or 35 siphoned from the soaps. It may still retain small amounts of soap in the form of a fine precipitate and it is therefore desirable to filter the oil to directly remove these materials. However, this step is not necessary, especially if the mixture 40 is given sufficient time to settle.

After the above treatment the oil can be directly distilled, preferably after degassing in the usual and known manner. The oil may be washed and/or dried before distillation, but such 45 procedure is not ordinarily necessary. Manifestly the possibility of avoiding these costly and cumbersome steps is a decided advantage.

Operation in this manner will avoid undue loss of the oil. After decanting a portion of the oil 50 will be retained by the solid soaps and can be recovered therefrom by obvious expedients such as salting out, acidification, gravity separation or centrifuging.

Since the ultimate purpose is the recovery of 55

vitamins contained in the oil, it will be realized that it is desirable to take precautions to avoid unnecessary destruction of the vitamins during the treatment. High temperatures should be avoided and it is advantageous to carry out the entire treatment in an inert atmosphere, such as in a nitrogen or carbon dioxide environment.

The following example illustrates the manner in which my invention is carried out to yield 10 distillates having improved properties as regards odor, vitamin content and which are substantially free of undesirable fatty acids.

Example

15 4600 gms. of pollack liver oil having a vitamin A potency of 10,600 units per gram, an acid value of 1.8 and free fatty acid content of .9 percent was heated to 40° C. 9 gms. of caustic soda dissolved in 40 cc. of water was added to the oil with 20 slow agitation. Agitation was continued until the flocculation point was reached. The mixture was allowed to settle, the oil siphoned off and filtered through a silicious filter bed. 4285 grams of refined oil having a vitamin A potency 25 of 12,200 units per gram and acid value of .033 was obtained. After degassing this was subjected to distillation in a small high vacuum still having the vaporizing and condensing surfaces separated by about 1 inch. The following table 30 indicates the course of the distillation and the character of the products.

Fraction No.	Still pressure, microns	Still T, °C.	Weight, grams	Percent cut	Vitamin A potency	Percent vitamin A	Acid value
1	3	135-185		.01	28,500	1.4	4.9
2	2.5	185-210	12	.28	240,000	5.6	1.85
3	2.5	210-220	85	.82	176,000	11.8	.98
4	2.0	220-230	89	2.10	100,000	17.2	.51
5	2.0	235	168	3.70	62,000	18.8	.31
6	2.0	235	220	5.10	39,000	16.4	.28
7	2.0	240	211	4.9	16,000	6.4	.15
8	2.0	240	251	5.9	9,600	4.7	.08
Residue			3,150		1,700	10.7	.08

45 The above shows the remarkably low acid value of the vitamin fractions after removing a relatively small preliminary fraction.

Although I have found it convenient to describe my invention by reference to particular oils, it is to be understood that it is in no way limited to the treatment of particular substances. Oils containing fat soluble vitamins in general, such as for instance dog fish, tuna, liver, menhaden and wheat germ oils or concentrates thereof may be treated in the manner described.

55 Molecular, or high vacuum distillation of vitamin containing oils yields concentrates of vitamins which are vastly superior to those produced by other methods. However, when a particularly rancid oil is distilled, odoriferous concentrates are obtained especially in the first fractions. An outstanding advantage of this invention is that fractions obtained from these sources when using the above described procedure are substantially bland and odorless. A further advantage is that the fractions, particularly the lower boiling fractions, are substantially free of fatty acids and in addition are of higher potency because of the absence of these diluting materials. It will be realized that since the fatty acids ordinarily distilled with these fractions, they could not have been easily removed by redistillation which, in any event, would have involved considerable expense and thermal loss. The alkali treatment prior to distillation overcomes these difficulties. It also increases the

time that a still can be operated without shutdowns to clean the vaporizing surface.

It has been found that fatty acids have a pro-oxidant activity and therefore hasten the oxidation of oxidizable substances with which they are associated. Their removal from the sensitive vitamin concentrates is therefore of increased importance. It has also been found that heating fatty acids with vitamin A causes its conversion into a substance which has approximately the same ultra violet absorption spectrum as vitamin A, but which is devoid of vitamin A activity. Removal prior to distillation prevents any possibility of loss due to this cause either during distillation or subsequent storage.

What I claim is:

1. The process for preparing a vitamin concentrate from an oil which contains fat soluble vitamins including Vitamin A esters and free fatty acids which comprises in combination, neutralizing the free fatty acids, without causing substantial saponification of the oil, separating the oil from the neutralized acids, subjecting the oil to high vacuum distillation and separating a distillate fraction containing a vitamin.

2. The process for preparing a vitamin concentrate from a marine animal oil which contains vitamins as well as free fatty acids which comprises in combination, neutralizing the free fatty acid content of the oil, without causing substantial saponification of the oil, separating the

30

substantially saponification of the oil, separating the

oil from the neutralized fatty acids, and subjecting the oil to distillation by heating it in the form of a thin film under a high vacuum and condensing vitamin molecules upon a condensing surface separated from the film by substantially unobstructed space.

3. The process for preparing a vitamin concentrate from a fish oil which contains vitamins as well as free fatty acids which comprises treating the oil with alkali sufficient to neutralize substantially all of the free fatty acid, but insufficient to appreciably saponify the oil, separating the oil from the soaps thus formed, and subjecting the oil to distillation by heating it in a thin film under a residual gas pressure of less than about .1 mm. and condensing vaporized molecules upon a condensing surface located at a short distance from the heated film.

4. The process for preparing a vitamin concentrate from a fish oil which contains vitamins as well as free fatty acids which comprises treating the oil with alkali in slight excess to that required to neutralize the free fatty acids, separating the oil from the soaps thus formed, and subjecting the oil to distillation by heating it in a thin film under a residual gas pressure of less than .1 mm. and condensing vaporized vitamin molecules upon a condensing surface separated from the film by a distance of less than about the mean free path of the molecules of residual gas.

5. The process for preparing a vitamin con-

centrate from a fish oil which contains vitamins as well as free fatty acids which comprises in combination, treating the oil with a solution of alkali in amounts sufficient to substantially neutralize the free fatty acids, but insufficient to cause substantial saponification of the oil, separating the oil from the resultant soaps and subjecting it to distillation by heating it in a thin film under a residual gas pressure of less than about .1 mm. and condensing vaporized molecules upon a condensing surface located at a distance from the heated film of between about $\frac{1}{2}$ and 4 inches.

6. The process for preparing a vitamin con-

centrate from a fish oil which contains vitamins as well as free fatty acids, which process comprises treating the oil with an aqueous alkali solution sufficient to neutralize substantially all of the free fatty acid contained in the oil, but insufficient to appreciably saponify the oil, separating the oil from the soap solution and directly subjecting the oil to distillation by heating it in a thin film under a residual gas pressure of less than about .1 mm., and condensing vaporized vitamin molecules upon a condensing surface located a short distance from the film.

KENNETH C. D. HICKMAN.
